UNITED STATES PATENT OFFICE.

EMIL J. SIMON, OF NEW YORK, N. Y., ASSIGNOR TO THE RADIO TELEPHONE COMPANY, OF NEW YORK, N. Y., A CORPORATION OF NEW JERSEY.

SPARK-GAP FOR RADIOTONE WIRELESS-TELEGRAPH SYSTEMS.

971,935.

Specification of Letters Patent.

Patented Oct. 4, 1910.

Application filed March 17, 1910. Serial No. 549,974.

To all whom it may concern:

Be it known that I, EMIL J. SIMON, a citizen of the United States, residing in the city, county, and State of New York, have 5 made a certain new and useful Invention in Spark-Gaps for Radiotone Wireless-Telegraph Systems, of which the following is a specification.

This invention relates to apparatus for 10 producing powerful electrical oscillations for use in the transmission of wireless signals.

The object of the invention is to provide 15 a simple and efficient construction of spark gap for use in connection with wireless apparatus of the nature referred to.

The invention consists substantially in the 20 construction, combination, location and relative arrangement of parts, all as will be more fully hereinafter set forth, as shown in the accompanying drawing, and finally pointed out in the appended claims.

Referring to the drawing:—Figure 1 is a 25 view in diagram illustrating one arrangement of circuit connections with which a spark gap construction embodying the principles of my invention is well adapted for use. Fig. 2 is a view in elevation, parts broken out and in section, showing a construction of spark gap embodying the principles of my invention.

In the practical use of wireless apparatus, a system known as the "singing spark" method has recently been proposed wherein 35 slowly damped waves are generated and radiated, which enable close tuning to be attained and difficulties resulting from interference to be eliminated, while at the same time securing greater efficiency over former methods in the radiated energy as 40 compared with the energy required in generating the waves.

In the singing spark method a great number of spark gaps are arranged in series 45 with each other, and in the use of the apparatus the sparks are quickly quenched thereby resulting in the generation and radiation of powerful slowly damped waves which are heard in the receiving instrument as a high clear note.

In the practical use of apparatus of this nature there is a great tendency of the sparks to concentrate at one point on the surface of one or another of the electrode plates or

disks, thereby forming protuberances, in- 55 crustations, pits or projections in one or the other, or both of the opposed surfaces between which the spark occurs, the formation of which tends still further to concentrate the spark discharge at that point, with the 60 result that irregularities in the action of the apparatus are produced which greatly impair its usefulness and efficiency, causing derangement of the proper functioning of the apparatus, and necessitating frequent re- 65 removals of the disks or plates in order to clean or polish anew the surfaces thereof. Even with the use of flat opposed surfaces of extended area such as are presented by plates or disks, these difficulties are encoun- 70 tered and have been found to be a serious obstacle to the attainment of satisfactory practical results.

It has heretofore been proposed to obviate this source of trouble by interposing mica 75 washers as insulators between the surfaces of adjacent plates. This expedient, however, has been found inefficient and unsuccessful for the reason that by the use of mica washers or rings it is impossible to se- 80 cure air tightness, and the exclusion of air from the space between adjacent electrode surfaces, in which space the spark occurs, is essential to success. The plates or disks are made of metal and the hard surfaces thereof 85 contacting with the hard unyielding surfaces of the mica rings or washers, fails to secure the degree of air-tightness which is essential.

In carrying out my invention, and in order 90 to attain the practical and successful exclusion of air from the spark gap spaces, thereby excluding the oxygen constituent of the air from such spaces, I have found that thin washers, gaskets or rings of soft elastic, 95 resilient material, capable of withstanding moderately high temperatures, interposed between the adjacent surfaces of the metal plates or disks composing the spark gap, enable me to attain most excellent results. 100 Washers, gaskets or rings of rubber compound will answer the requirement, and, when the metal disks or plates are maintained at a sufficiently low temperature, the use of ordinary para rubber will suffice. 105

The interposed washers or gaskets must be of such nature as to insulate the metal plates or disks from each other, and also

such as to resist the puncturing action of the current employed to generate the sparks. Not only do the thin sheets or washers of rubber or rubber compounds answer these requirements, but they are also yielding and resilient, and when the plates or disks are clamped tightly together with the washers or gaskets interposed therebetween, said washers or gaskets yield and compress sufficiently to effect an exclusion of air from the spark gap spaces, and hence the spark gap structure employing such interposed gaskets or washers, can be used continuously without disturbing, or deranging the proper and orderly operation of the device or the proper functioning of the apparatus due to the formation of protuberances, projections, incrustations or pits in the surfaces of the plates or disks, and the consequent concentration of the sparks at such points. I am also thus enabled to maintain a quick quenching of the sparks which is necessary in order to obtain such a radiation of waves as will produce a clear musical note in the receiving apparatus. I am also enabled to avoid the necessity for frequent removals of the plates or disks to clean or polish the surfaces thereof.

In the accompanying drawing I have shown a construction and arrangement of spark gap embodying the principles of my invention, and wherein the spark gap is shown as composed of a plurality of metal disks 4, superimposed or piled up upon each other. In practice I employ copper disks. Each disk is provided with a rim or peripheral portion 5, of less thickness than the body portion of the disk, thus providing for an efficient radiation of any heat developed in the disks while the apparatus is in operation. Each disk is provided with a circularly arranged groove or channel 6, in each face thereof, the portions 7, of the disks encompassing the grooves 6, constituting bearing surfaces between which the thin resilient washers or gaskets 8, are interposed when said disks are assembled. These interposed washers or gaskets also serve to insulate as well as to slightly off-set the disks from each other, thereby producing the air tight spaces 9, between the opposed surfaces of adjacent disks. The sparks occur in these air tight spaces.

Metal disks to the number of twenty or thirty, more or less, having the construction and relation above described, are ordinarily employed, and by the use of thin soft resilient gaskets, rings or washers, in accordance with my invention, I am enabled to attain a substantially air tight spark gap wherein a quick quenching of the sparks is secured, and concentration of the spark discharge at any particular point in the surface of any disk is prevented.

The disks may be assembled in any suit-

able manner. A simple arrangement is shown in Fig. 2, wherein the disks 4, are piled upon each other with the thin soft resilient washers 8, interposed therebetween, the disks being clamped between insulated heads 11, 12, mounted in a frame 13, supported on insulating legs 14. A screw 16, acting on one head serves to secure a tight clamping action of the disks upon each other. The leads 18, of the circuit connections are respectively connected to the heads 11, 12.

While my invention is shown and described as being employed in connection with a specific structure of metal electrode disk, and a specific construction of assemblage thereof, it is obvious that in its broadest scope, as defined in the claims, my invention is not to be limited or restricted to any specific structure or manner of assembling of the disks.

In Fig. 1 I have shown a circuit arrangement in connection with which my invention is adapted for use, and wherein A is a generator, in this case an alternating current generator of 110 volts and 500 cycles, though, obviously, my invention is not to be limited or restricted in these respects. The circuit of the generator is shown coupled through the primary and secondary coils P. S. of a resonance transformer, to a circuit containing the spark gap, indicated at G, and which is shunted by a capacity C, and an inductance J, shown as variable. This oscillating circuit is shown coupled adjustably to a coil L¹, in the antenna system, and which system includes the antenna A¹, the adjustable loading coil L², the coil L¹, and an ammeter A².

While I have shown one arrangement of circuit connections and antenna system suitable for use in connection with a radiotone spark gap embodying the principles of my invention, I do not desire to be limited or restricted to the particular circuit arrangements shown, as many others may be equally well adapted for use in this connection. But

Having now set forth the object and nature of my invention, and a construction and arrangement embodying the principles thereof, what I claim as new and useful, and of my own invention, and desire to secure by Letters Patent is,—

1. In an apparatus for producing powerful electrical oscillations, a plurality of electrodes having soft rubber gaskets interposed therebetween.

2. In an apparatus for producing powerful electrical oscillations, a plurality of metal disks having thin soft rubber gaskets interposed therebetween to form short air-tight sparking spaces between the opposed surfaces thereof.

3. In an apparatus for producing powerful electrical oscillations, a plurality of

metal disks superimposed the one upon another, means for clamping said disks upon each other, and soft rubber gaskets interposed between the opposed surfaces of adjacent disks.

4. In an apparatus for producing powerful electrical oscillations, a plurality of metal disks superimposed the one upon another, and having bearing surfaces formed in the opposing faces thereof, and soft rub-

ber gaskets interposed between the bearing surfaces of adjacent disks.

In testimony whereof I have hereunto set my hand in the presence of the subscribing witnesses, on this 28th day of February 15 A. D., 1910.

EMIL J. SIMON.
